UNITED STATES PATENT OFFICE.

LAWRENCE NEUMASTER, OF EVANSCVILLE, INDIANA.

CLOTHES-HOOK.

1,209,613.

Specification of Letters Patent. Patented Dec. 19, 1916.

Application filed April 17, 1916. Serial No. 91,683.

To all whom it may concern:

Be it known that I, LAWRENCE NEUMASTER, a citizen of the United States, residing at Evansville, in the county of Vanderburg and State of Indiana, have invented new and useful Improvements in Clothes-Hooks, of which the following is a specification.

This invention relates to improvements in supporting hooks, and more particularly to that class thereunder known as wall hooks, primarily adapted to be used for supporting clothes and like articles thereon, and so designed as to prevent any accidental slipping or dropping of the apparel from the supporting hooks. To this end, use is made of a pair of clothes supporting hooks, and a clothes clamping hook, the clothes clamping hook being mounted for vertical swinging movement with respect to the supporting hooks, and upon the swinging movement of the clamping hook in one direction, will clamp the clothes firmly upon the stationary hooks and prevent the garment supported thereon from falling or dropping on the floor.

With the above and other objects in view, the invention consists in the novel features, details of construction, and combination of parts which will hereinafter be more fully set forth, illustrated in the accompanying drawing, and pointed out in the appended claims.

Figure 1 is a perspective view, showing the device in active position; Fig. 2 is a similar view to Fig. 1, showing the clamping hook in inactive position; and Fig. 3 is a perspective view of the device removed from the wall, with the clamping hook illustrated in a perpendicular position, the clamping position of the clamping hook being illustrated in dotted lines.

Referring more particularly to the accompanying drawing, in which like characters of reference refer to corresponding parts, 5 designates a frame constructed from a single strand of stout wire, forming the frame with a pair of spaced parallel side limbs 6 and 7. The upper extremities 45 of the side limbs are bent forwardly and angularly in converging relation one with the other to provide a two-part upper stationary hook 8, having a bill portion 9. The lower extremity of the limb 6 is bent 50 in an inward lateral direction, and looped around the side limb 7 as at 10, to provide

the frame with a lower cross bar 11. The lower extremity of the opposite side limb, or the side limb 7, is continued below the plane of the lower cross bar 11, in an inward and forward direction, indicated by the character 12, thence upwardly, thence downwardly, and rearwardly directed, designated by the character 13, and thence looped around the central portion of the 60 lower cross bar 11, as at 14, forming contiguous with the frame 5, a lower stationary hook 15. This stationary hook 15 is of lesser length than the upper hook 8, and is positioned below and in superposed relation 70 therewith. An upper cross bar 16 is connected with the upper extremities of the side limbs 6 and 7 of the frame, by looping the same therearound as at 17, forming the upper cross bar with eyes 18. The portions of the cross bar forming the eyes are extended outwardly and laterally from the side limbs 6 and 7 to provide trunnions 19. The looped portion 14 is extended upwardly in parallelism and between the side 75 limbs 6 and 7, and looped around the metal portion of the cross bar forming a central base bar 20, terminating in a rearwardly extending securing prong 21. It will be obvious from the drawing that by the insertion 80 of this prong 21 within a fixed support, such as a wall or the like, designated generally by the reference character 22, will hold the frame in contact therewith, and support the upper and lower rigid hooks in 85 supported position.

I employ in connection with a supporting hook of the above referred to character, a clamping hook 23, which is constructed from a single strand of wire including a bill portion 24, and spaced side limbs 25. The limbs 25 of the clamping hook are bent to provide eyes 26 for engagement with the trunnions 19 of the uppermost cross bar 16, and mounting the hook exteriorly of the upper and lower rigid hooks 8 and 15 respectively, for a vertical swinging movement. In order to have a clear understanding of the invention, it might be further stated that when the articles of apparel are hung upon the bill 95 portions of the respective upper and lower hooks, and it is desired to clamp the same against any accidental displacement, a downward pull on the clamping hook will bring the same over and in straddling relation 100 with the said upper and lower stationary hooks, and in clamping engagement with the 105

articles of apparel suspended thereon. If necessary, after the hook has been swung to the position as described, the user of the hook can support further garments upon the bill portion 24 thereof, and by subjecting the clamping hook to the weight of the apparel, will aid in holding the same in a lowered or clamping position. The clamping hook 23 can be swung below the lowermost stationary hook 15, until the limb portions thereof engage with the lower cross bar 11, and thereby provide further efficiency for the hook accommodating the supporting of several articles of apparel.

From the foregoing description, taken in connection with the accompanying drawing, the advantages of construction and of the method of operation will be readily apparent to those skilled in the art to which the invention relates, and while I have described the principles of operation of the invention, together with the device which I now consider to be the best embodiment thereof, I desire to have it understood that the device shown is merely illustrative, and that such advantages may be made when desired as are within the scope of the claims appended thereto.

I claim:

1. A clothes hook, comprising a frame formed from a single strand of wire including side limbs, the upper extremities of the side limbs being bent to provide an upper hook, the lower extremity of one of the side limbs being looped around the other of the

side limbs of the frame, forming the frame with a lower cross bar, the lower terminal of the other of said side limbs of the frame being bent to provide a stationary hook, the strand of wire forming the stationary hook being looped around the cross bar of the frame and extended rearwardly to provide an attaching member, and a clamping hook pivotally mounted on the frame of said hook for a vertical swinging movement.

2. A clothes hook, comprising a frame formed from a single strand of wire including side limbs, the upper extremities of the side limbs being bent to provide an upper hook, the lower extremity of one of the side limbs being looped around the other of the side limbs of the frame, forming the frame with a lower cross bar, the lower terminal of the other of said side limbs of the frame being bent to provide a stationary hook, the strand of wire forming the stationary hook being looped around the cross bar of the frame and extended rearwardly to provide an attaching member, an upper cross bar connecting the limbs of the frame together, and formed with trunnions, a clamping hook pivotally mounted on the trunnions of the uppermost cross bar for a vertical swinging movement.

In testimony whereof I affix my signature 65
in presence of two witnesses.

LAWRENCE NEUMASTER.
